No. 36,461.

Patented July 21, 1903.

UNITED STATES PATENT OFFICE.

WILLIAM F. CAPITAIN, OF ST. LOUIS, MISSOURI, ASSIGNOR TO THE AMERICAN TYPE FOUNDERS' COMPANY, OF NEWARK, NEW JERSEY, A CORPORATION OF NEW JERSEY.

DESIGN FOR A FONT OF TYPE.

SPECIFICATION forming part of Design No. 36,461, dated July 21, 1903.

Application filed May 14, 1903. Serial No. 157,194. Term of patent 7 years.

To all whom it may concern:

Be it known that I, WILLIAM F. CAPITAIN, a citizen of the United States, residing at St. Louis, Missouri, have invented a new, original, and ornamental Design for a Font of Type, which is fully shown in the accompanying typographical impression, to which reference is made.

I claim as my invention—

10 The ornamental design for a font of type, substantially as shown in the accompanying typographical impression.

In testimony whereof I have signed my name to this specification in the presence of two subscribing witnesses.

WILLIAM F. CAPITAIN.

Witnesses:

A. E. PETENO,
J. A. WINKELMAN.
